[57] CLAIM

The ornamental design for a stackable chair or the like, substantially as shown and described.

DESCRIPTION

FIG. 1 is a front elevation view of the stackable chair or the like showing my design;

FIG. 2 is a right side elevation view of the stackable chair or the like, the left side being of similar ornamentation, and

FIG. 3 is a top plan view of the stackable chair or the like.

The undisclosed rear surface of the backrest is the same in appearance as the front thereof.
